UNITED STATES PATENT OFFICE.

WILLIAM P. BRADLEY, OF SEWICKLEY, PENNSYLVANIA.

METHOD OF MOUNTING PATTERNS ON MATCH BOARDS.

Application filed February 16, 1926. Serial No. 88,718.

This invention relates to methods of mounting patterns on match-boards and has for one of its objects the provision of an improved method whereby the patterns can be accurately mounted in materially less time than by any of the methods now in use.

Another object is to provide a method that may be carried out by unskilled labor, thereby materially reducing the labor cost for mounting patterns.

A further object is to provide a method of mounting patterns on match-boards including the several novel steps hereinafter described and illustrated in the accompanying drawings.

In the drawings:

Figure 1 is a plan view of one of the mounting frames.

Figure 2 is a sectional view taken on the line II—II of Figure 1.

Figure 3 is a plan view of one of the mounting frames positioned on a match-board and having the outline of the drag part of the patterns thereon.

Figure 4 is a sectional view taken on the line IV—IV of Figure 3.

Figure 5 is a plan view of the second frame superimposed on the first frame on the match-board and having the outline of the cope part of the patterns thereon.

Figure 6 is a sectional view taken on the line VI—VI of Figure 5.

Figure 7 is a plan view of the frame having the outline for the drag part of the patterns thereon, arranged on the match-board and having the drag part of the patterns secured thereto.

Figure 8 is a sectional view on the line VIII—VIII of Figure 7.

Figure 9 is a plan view of the frame having the outline for the cope part of the patterns thereon, arranged on the match-board and having the cope part of the patterns secured thereto.

Figure 10 is a sectional view taken on the line X—X of Figure 9.

Referring more particularly to the drawings, the letters A and B designate the layout frames used in carrying out my method, such frames being of duplicate construction and comprising a wooden frame 2 of slightly smaller size than the match-board 3 and provided with dowel-holes 4 adapted to align with other dowel-holes 5 in the match-board. Dowel-pins 6 are adapted to be passed through the dowel-openings or

holes 4 and 5 to center the frames A and B on the match-board.

The frames A and B are adapted to have a sheet of transparent drawing paper or other similar material 7 removably secured thereon by thumb-tacks 8, and the outline or position markings of the pattern parts are adapted to be made on the material 7 by a pencil or other marker.

The drag parts of the patterns are designated by the numerals 9 and 10, and the cope parts by the numerals 11 and 12. The numeral 14 designates a filler-board which is fitted within the frame having the outline of the drag parts of the patterns thereon to support the paper 7 on said frame when the other frame is superimposed thereon.

In carrying out my invention the frames A and B are first prepared by securing the paper 7 on the wooden frame members 2. The prepared frame A is then positioned on the match-board 3, with the paper side down against the board, and centered by inserting dowel-pins 6 in the dowel-pin holes 4 and 5 in the frame and match-board respectively.

When the frame A has thus been positioned and centered, the drag parts 9 and 10 are positioned on the paper 7 and the outline of the parts 9 and 10 marked or drawn on the paper by a pencil or other similar instrument, as indicated at 15 and 16.

After the outlines 15 and 16 are made, the parts 9 and 10 are removed, the frame A is inverted on the match-board 3, and the filler-board 14 is placed in the frame to fill the space between the paper 7 on the frame A and the match-board. The second frame B is now superimposed or mounted on top of the frame A with its paper side down in contact with the paper on the frame A. The paper on the frame B at least being transparent, the outlines on the paper of frame A will be visible through the paper on frame B.

The frames A and B are then centered or aligned with each other and centered on the match-board by passing the dowel-pins 6 through the holes 4 in the frames and the holes 5 in the match-board. The cope sides or parts of the patterns are now arranged on the paper 7 on the frame B in alignment with the outlines or markings on the paper 7 on frame A which are visible through the paper on the frame B, and the outlines of the cope parts are drawn on the paper on the frame B, as indicated at 17 and 18. The

cope sides or parts of the patterns are then removed and the frames and filler-board 14 removed from the match-board 3.

The frame A is then mounted on the 5 match-board 3 with the paper side against the board and centered by inserting the dowel-pins 6 in the holes 4 and 5. The drag sides or parts of the patterns 9 and 10 are then positioned on the paper in alinement 10 with the previously made outlines 15 and 16, and such parts are then nailed or otherwise securely mounted on the board. The frame A is then removed and the paper cut or torn away from around the pattern parts.

15 The match-board 3 is then inverted and the frame B, having the outlines 17 and 18 of the cope parts thereon, is positioned on the other side of the match-board and centered by inserting the dowel-pins 6 in the 20 holes 4 and 5. The cope sides or parts 11 and 12 of the patterns are then positioned on the paper in alinement with the previously made outlines 17 and 18, and such parts are then nailed or otherwise securely mounted 25 on the board. The frame B is then removed and the paper cut or torn away from around the pattern parts.

The match-board 3 is now ready for use in forming the molds.

30 If the outlines of the drag and cope parts of the pattern are different or where there are several loose pieces in the cope part, cross lines are drawn on the joint side of the pattern parts and continued up the sides of the 35 pattern parts, as at 20. Pencil match marks 21 are then made on the paper 7 to correspond with the lines 20 of the drag part. After the outline of the drag part is made and the part removed from the paper the 40 match marks 21 are connected by drawing straight lines 22. The cope piece or pieces of the pattern may then be located in proper position relative to the outline of the drag piece by bringing the match cross lines 20 45 on the cope into alinement with the lines 22 on the paper of frame A when making the outline of the cope piece.

While I have shown my invention as used for mounting the drag and cope parts of the 50 patterns on the opposite sides of the same match-board, it will be understood that I do not wish to be limited thereto, since it may be used to mount the drag and cope parts on separate boards or on the same side 55 of a single board if desired.

It will also be understood that I do not wish to be limited to the use of the specific apparatus shown and described for carrying out my invention since various modifications of this apparatus may be used without departing from the scope of my novel method as defined in the appended claims.

I claim:

1. The method of mounting patterns on match-boards which consist in marking the

position of the one half of the pattern on a sheet of paper, superimposing a second sheet of transparent paper over said first paper, marking the position of the other half of the pattern on said second sheet of paper in accordance with the markings on said first named sheet which are visible through said superimposed transparent sheet, centering said sheets of paper on a match-board, positioning the patterns on said sheets of paper 75 according to the marked positions, and securing said patterns to said board.

2. The method of mounting patterns on match-boards which consists in marking the 80 position of the drag side of the pattern on a sheet of paper, marking the position of the cope side of the pattern on a second sheet of paper, centering said sheets of paper on a match-board, positioning the pattern parts 85 on said sheets of paper according to the marked positions, and securing said pattern parts to said board.

3. The method of mounting patterns on match-boards which consists in marking the 90 position of the drag side of the pattern on a sheet of paper, marking the position of the cope side of the pattern on a second sheet of paper, centering said sheets of paper on the opposite sides of a match-board, positioning the patterns on said sheets of paper according to the marked positions, and securing 95 said patterns to said board.

4. The method of mounting patterns on match-boards which consists in marking the 100 position of the drag side of the pattern on a sheet of paper, marking the position of the cope side of the pattern on a second sheet of paper, centering said sheets of paper on the opposite sides of a match-board, positioning the patterns on said sheets of paper according to the marked positions, securing said 105 patterns to said board, and removing the paper from around said patterns.

5. The method of mounting patterns on match-boards which consists in marking the 110 position of the one half of the pattern on a sheet of paper, superimposing a second sheet of transparent paper over said first paper, marking the position of the other half of the pattern on said second sheet of paper in accordance with the markings on said first named sheet which are visible through said superimposed transparent sheet, centering said sheets of paper on the opposite sides 115 of a match-board, positioning the patterns on said sheets of paper according to the marked positions, securing said patterns to said board, and removing the paper from around said patterns.

6. The method of mounting patterns on match-boards which consists in securing a 125 sheet of paper on a frame, marking the position of the drag part of the pattern on said sheet of paper, securing a second sheet of paper on a second frame, centering said 130

frames, marking the position of the cope part of the pattern on said second sheet of paper in proper alinement with the markings on said first sheet of paper, positioning and centering said frames with the paper sheets secured thereto on a match-board so that said paper sheets are in contact with and supported by said board, positioning the pattern parts on said paper sheets in alinement with the markings thereon, and securing the pattern parts to said board.

7. The method of mounting patterns on match-boards which consists in securing a sheet of paper on a frame, marking the position of the drag part of the pattern on said sheet of paper, securing a second sheet of paper on a second frame, centering said frames, marking the position of the cope part of the pattern on said second sheet of paper in proper alinement with the markings on said first sheet of paper, positioning and centering said frames with the paper sheets secured thereto on the opposite sides of a match-board so that said paper sheets are in contact with and supported by said board, positioning the pattern parts on said paper sheets in alinement with the markings thereon, securing the pattern parts to said board, and removing the frames and paper from said board.

8. The method of mounting patterns on match-boards which consists in providing a pair of frames having suitable dowel-holes therein adapted to aline with other dowel-holes in the match-board and to receive dowel-pins for centering said frames on said board, securing a sheet of transparent paper on one of said frames, marking the position of the drag part of the pattern on said sheet of paper, securing a second sheet of transparent paper on the other of said frames, superimposing said last named frame over said first named frame and alining said frames by passing dowel-pins in the dowel-holes in said frames, marking the position of the cope part of the pattern on said second sheet of paper in alinement with the

marking on said first sheet which marking is visible through said transparent second sheet, positioning said frames with the paper sheets secured thereto on a match-board so that said paper sheets are in contact with and supported by said board, centering said frames and paper sheets on said board by passing dowel-pins through the dowel-holes in said frames and said board, positioning the pattern parts on said paper sheets in alinement with the markings thereon, and securing the pattern parts to said board.

9. The method of mounting patterns on match-boards which consists in providing a pair of frames having suitable dowel-holes therein adapted to aline with other dowel-holes in the match-board and to receive dowel-pins for centering said frames on said board, securing a sheet of transparent paper on one of said frames, marking the position of the drag part of the pattern on said sheet of paper, securing a second sheet of transparent paper on the other of said frames, superimposing said last named frame over said first named frame and alining said frames by passing dowel-pins in the dowel-holes in said frames, marking the position of the cope part of the pattern on said second sheet of paper in alinement with the marking on said first sheet which marking is visible through said transparent second sheet, positioning said frames with the paper sheets secured thereto on a match-board so that said paper sheets are in contact with and supported by said board, centering said frames and paper sheets on said board by passing dowel-pins through the dowel-holes in said frames and said board, positioning the pattern parts on said paper sheets in alinement with the markings thereon, securing the pattern parts to said board, and then removing said frames and said paper sheets.

In testimony whereof, I have hereunto set my hand.

WILLIAM P. BRADLEY.
